UNITED STATES PATENT OFFICE.

JAMES W. BRYCE, OF BINGHAMTON, NEW YORK, ASSIGNOR TO THE INTERNATIONAL TIME RECORDING COMPANY OF NEW YORK, N. Y., A CORPORATION OF NEW YORK.

MULTIPLYING MACHINE.

Application filed April 22, 1921. Serial No. 463,534.

The invention subject of my present application for Letters Patent is a new and improved multiplying machine. The machine is provided with means such as keys which correspond to digits and these keys are in two sets or banks, those of one bank corresponding to the digits of the multiplicand and those of the other set or bank to the digits of the multiplier. When the keys of these respective banks are depressed or set, the machine is adapted by a simple and single operation, such as the mere turning of a handle to perform the entire operation of multiplying the two numbers thus selected and of registering, recording or indicating the product and resetting or clearing the mechanism. I have devised the machine in this form, but the specific arrangement of the parts or their construction are not of the essence of the invention and may be modified and varied at will.

10 The invention embodies and depends for its success upon the discovery by me of a certain element or piece of mechanism which has no name in the art and which, for want of a better designating term I shall hereinafter call a multiplying slug, adopting this term from shop parlance where it is used to define the said new device.

15 This multiplying slug is constructed in any suitable form according to the following principle: Such a device as a small rectangular insulating plate carries along each vertical edge two rows of ten contacts which may be assumed to be numbered downward from 0 to 9 and for use in the machine nine of such slugs are provided for each column of figures or order of units in the multiplier. The oppositely disposed contacts on each side of the slug are connected across according to a fixed rule determined by the multiplication table. Let us take any slug, for example, that corresponds to the number 2 unit in the multiplier—the top contacts are connected directly across; the second contact on the left side is connected to the third contact on the right on the theory that 2 times 1 is 2. The third contact on the left is con-

nected to the fifth contact on the right on the theory that 2 times 2 is 4 and in similar manner the fourth contact on the left is connected to the seventh contact on the right and the fifth on the left to the ninth on the right.

The sixth contact or that numbered 5 on the left is connected to the first or zero contact on the right, the seventh to the third, the eighth to the fifth, the ninth to the seventh and the tenth to the ninth.

On the opposite side of the slug are contacts which are releated to and control the tens column in the product. Of these the first five contacts on the left are connected to the first or zero contact on the right, while the remaining five contacts on the left are all connected to the second or unit contact on the right, because two times five is ten; two times six is twelve; and so on. Here it will be noted that the multiplications give a resultant characteristic of one in the tens column of the product.

Consider now a very simple case of multiplication, say 2 times 4. One of the contacts or that corresponding to 4 units in the multiplicand is connected with a source of current by the depression of the 4 unit key, and by the operation of the selective mechanism the multiplying slug for the 2 units is moved up so that the ten contacts on its left engage the ten stationary multiplicand contacts including the active contact 4. The result of this is to connect this 4 contact with the 8 contact on the right of the slug and if by any proper means the latter is caused to close the proper magnetic circuit in a counter the units wheel of that device will be moved eight spaces.

Take as another simple example, to multiply 6 by 2. The multiplicand contact corresponding to 6 units is rendered active, multiplying slug corresponding to 2 is moved to operative position whereby the seventh contacts on both sides of the slug to the left engage with the corresponding or 6 units contacts of the multiplicand. By this means the 2 product contact to the right in the unit column is rendered active and the 1 product contact to the right on the tens column also,

so that if these contacts are properly arranged they will operate to turn the units wheel of a counter 2 steps and the tens wheel 1.

6 This is the principle of operation of the new device. How it is carried out in the case of numbers containing two or more orders of units in either multiplicand or multiplier will be more fully explained in the 10 accompanying specification.

In the accompanying drawings:

40 Figs. 14, 15, 16, 17, 18 and 19 are diagrams which are necessary to a correct understanding of the invention.

The counter employed in the present machine which is marked 10 may be of any approved type adapted to display totals on indicating wheels and to set up the totals 45 on type wheels. The particular counter herein shown and described is that set forth in patent to C. D. Lake, No. 1,307,740, dated June 24, 1919. This counter or totalizer contains a number of wheels of different 50 denominational orders and the controlling of the operation of these wheels is dependent upon circuits being closed at definite points in the rotation of a shaft which bears the totalizer wheels. The closure of these 55 circuits clutch the individual totalizer wheels to the shaft and the totalizer wheels are released at a predetermined point in the rotation of the shaft.

The counter controlling magnets are 60 shown at 11 in Fig. 3, and the driving and resetting of the counter is effected by means of a hand lever 12, Figs. 1 and 2. The lever 12 is fixedly mounted on a gear disk 13, and to compel a complete stroke of the handle a 65 full stroke ratchet and pawl mechanism 14

of the usual form is provided. Parts marked 15 and 16 and 89 serve to stop the rotation of the handle after one complete revolution thereof. The initial handle movement through the gear teeth 18, pinion 20, etc., restores the counter to zero.

In the present machine, for the proper cyclic operation it is necessary that the counter driving shaft make four complete revolutions for each single revolution of the 75 handle. This is necessary, since there are four complete adding steps in the cycle employed in the present machine. To effect this rotation of the shaft a gear 21 (Fig. 3) is provided mounted upon a shaft 22 extending to and intermeshing with the gearing diagrammatically illustrated in Fig. 3 to effect the rotation of the counter drive shaft. The pinion 21 is adapted to intermesh with gearing 23 and actuate the counter after the resetting operation is completed. Gear 23 is adapted to impart the first two revolutions to the counter. A gear 24 upon its intermeshing with the driving pinion 21 is adapted to impart the second 90 two revolutions to the counter.

To control the multiplying operation a keyboard of conventional form is provided. This consists of a series of multiplier keys 95 25 and a series of multiplicand keys 26. These keys are preferably of distinctive color or design and it will be understood that any number of rows of keys may be employed as desired. In the present embodiment tens and units multiplier and multiplicand keys only are shown. The keys upon being depressed are adapted to be latched down by the usual flexible keyboard latch or detent 27, Fig. 3. At a proper time in the cycle the latch plate 27 is tripped by means of a suitable pivoted tripping member 28 which is operated by a pin 29 on the gear disk. This construction is common in adding machines, and it is sufficient here to state that the keys are pressed upwardly by individual springs and the depression of one key releases the others. Each of the multiplier keys and each of the multiplicand keys are adapted, upon depression,

100 to close contacts designated 30. These contacts are shown diagrammatically in the circuit diagram, Fig. 17. One side of the circuit extending to these contacts 30 for the multiplier keys passes through cam contact controlling devices 31, 32 which permit a flow of current from the line and the battery 32^a at the proper time in the operation 105 of the machine. It may be here explained that there are four pairs of cam contact

110 devices which are respectively marked 31, 32, 33, and 34 in Fig. 4. These cam contact devices are mounted upon a shaft 35, which shaft makes one complete revolution for each revolution of the shaft 36 (see Fig. 4). The shaft 36 in turn is directly connected to 115 120 125 130

the driving handle of the machine. The closure of the individual contact circuits by the keys of the multiplier is adapted to select a particular multiplying slug for operation. This selection is effected through magnets 38, one magnet being provided for each multiplying slug. Upon the closure of a circuit by the keys of the multiplier and the closure of the cam of the main circuit by the 10 cam contact devices current is allowed to flow to one or the other of these magnets to energize the same and attract the armatures 39. These individual armatures are connected by individual rods 40 to plates 41 which are pivotally mounted upon a rock shaft carrying the rock lever 42. The lever 42 cooperates with a cam member 43 fixed on shaft 35 and having two high portions so as to rock the lever 42 against the tension 20 of a return spring 42^a, Fig. 7, in a counter-clockwise direction twice for each revolution of the handle. Upon the swinging of any latch plate 41 a linkage 44 will be disposed into such position as to cooperate with the 25 depending finger 45 under a particular multiplying slug and thereafter elevate the same upon the rocking of the lever 42. In the illustrated embodiment there are nine multiplier keys for the units column and nine for the tens column. There are, therefore, accordingly, eighteen multiplying slugs utilized, and the depression of any key will 30 select its particular multiplying slug for elevation.

35 For a further understanding of the machine, a brief explanation will be given of the multiplying steps which are performed by reference to an example. It will be considered that 47 is to be multiplied by 86.

40 Multiplying 6 by 7 gives 42 and 6 by 4 gives 24. The organization of the machine, however, is such that the two in the units column of the sub-product 42 must be set up concurrently in the machine with the 45 four in the tens column of the product of 6 times 4. This amount will be first added in to the counter. Subsequently there will be an adding in of 24 which constitutes the multiplication of 6 times 4 in the hundreds column and the multiplication of 6 times 7 in the tens column. These amounts being turned into the counter, we still have to add in the multiplication of 8 times 47 with proper allowance for the decimal point.

50 Multiplying 8 times 7 gives 56 and 8 times 4 gives 32. In adding these sub-multiplications into the counter the 6 will be added in the tens column of the counter concurrently with the adding in of 2 derived from the multiplication of 4 times 8 in the hundreds column. Finally, upon the last counter revolution there will be added in 5 in the hundreds column and 3 in the thousands column. From the above it will be 55 seen that in any given multiplication the adding in of the amount involving two characteristic places is carried out in two successive counter cycles. 42, for example, derived by the multiplication of 6 times 7 is not added in all at once, but the 4 in the tens column is added in at the second revolution. For the purpose of thus factoring the multiplying operation, I employ not only the selecting of the slugs for operation as heretofore explained, but also employ a sunflower device having a number of sectors which in number correspond to the number of columns or different orders in the product. These sunflower devices are provided with switch arms which successively contact 75 with the different sectors upon the successive counter revolutions. In the embodiment shown where four counter revolutions are employed the sunflowers are divided into four sectors and the contactor operation is 80 so timed that it passes through the first sector during the first revolution of the counter and through the second sector during the second revolution, and so on.

85 The sunflower devices comprise a plurality of insulated segments 46, 47, 48 and 49 (Fig. 4). These segments are provided with individual contacts arranged in successive spaced sectors, as best shown in Fig. 5, 50 being the first sector, 51 being the second, 52 the third, and 53 the fourth. The segments or sunflowers proper are fixedly supported in the machine by means of the brackets 54, see Fig. 3 for instance. Extending through the segments is a shaft 90 56 which is journaled for rotation in the machine frame. A clutch disc 57^b having a hub portion 57^c is fixed on the shaft. Said disc carries a pawl 57 spring-pressed into engagement with a ratchet 57^a. The ratchet 100 56 is fixed on a sleeve 57^d which is loosely mounted on the shaft 56. Also fixed on the sleeve is a pinion 58 meshing with a segment gear 59 on a lever 60, Fig. 3, pivoted at 60^a and having a follower roller cooperating 105 with a cam 61^a fixed on the shaft 36. Downward movement of the segment gear as viewed in Fig. 3 will cause clockwise rotation of ratchet 57^a as viewed in Fig. 9. And this will, through the pawl 57 and disc 57^b 110 cause rotation of shaft 56. Upward movement of the segment gear will cause the reverse movement of the ratchet 57^a, but the shaft 56 will remain idle. A pawl 57^c may be employed to prevent retrograde movement of the disc 57^b. As shown, the cam 115 61^a is of a box type and is so arranged as to first permit an initial dwell of the sector lever 60 during the resetting of the counter. Thereafter, the first rise rocks the sector in 120 turn rotating the shaft 56 and causing contact blades 61, 62, 63, 64, etc., to sweep over the contact points of the first sector 50 of the sunflowers. This operation takes place 125 during the first revolution of the counter, 130

the digital steps of which are synchronized with the passage of the sunflower brushes 61 over the contacts on the sunflowers by reason of the connection of the counter 5 clutch shaft 10^a to shaft 36 through the gear chain 10^b and the connection of the brushes 61 to the same shaft through the segment gear 59 and its actuating cam 61^a. Upon the second revolution of the counter 10 the next cam rise sweeps the switch arm over the second contacts 51. Following this there is a period of dwell in the cam to permit the contact arms to remain stationary during the restoration of the multiplying 15 slugs prior to a second operation. Thereafter, there are two or more elevated portions on the cam which effect the sweeping of the contactors over the contact points of sectors 52 and 53, respectively. After the 20 switch blades have made one complete revolution the lever 60 is restored, and during this restoration movement the switch blades remain stationary on account of the ratchet and pawl connection.

25 The number of sunflower units employed will depend upon the number of wheels which are to be operated to display the product. As shown, there are four of these sunflowers. Each sunflower corresponds to 30 a particular denominational order of counter magnet 11 and the common contacting brush of each sunflower is wired to its corresponding counter magnet 11. Referring now to the diagram, Fig. 15, the arm 61 is connected to the units counter magnet 11, 62 to the tens counter magnet 11^a, 63 to the hundreds counter magnet 11^b, and 64 to the thousandths counter magnet 11^c. These 35 arms, when they establish a current through 40 a live contact of the sunflowers, serve to clutch the individual registering wheels to the register shaft and effect the addition in the usual manner.

Multiplying slugs.

45 In the present embodiment it has been assumed that there are two rows of keys, units and tens, in both multiplier and multiplicand banks. For each multiplier key 50 there is a corresponding multiplier slug, or eighteen all together. These slugs are all of substantially the same mechanical construction, but differ only in the nature of their cross or transposing circuit connections. 55 Referring to Figs. 7 and 8, each slug comprises a metal plate 65 passing through a rectangular plate of insulating material 66. Each end of the metal plate is slotted and through these slots pass guide bars 67. All 60 of the slugs, except the particular ones selected for elevation, are normally held down by spiral springs 68. Along the left edge of each plate 66 are ten evenly spaced contacts 69, and upon the rear edge of the 65 plate at the same side thereof are corre-

spondingly evenly spaced contacts 70. At the right edge of the insulating plate there are corresponding contacts 71 and 72. The slug assembly as a whole and the spring contacts 69, 70, 71 and 72 are arranged to 70 slide between insulated bars 73, 74, which are correspondingly provided with ten evenly spaced contact plates 75, 76 and 77, 78, as shown in Fig. 8.

Each multiplying slug carries two sets of 75 transposition wires, one set marked 79 on one side of the insulated plate, and the other upon the rear side. The arrangement of transposition wiring is best shown in Fig. 14, which shows the front and back wiring 80 for each individual slug. The transposers 79 are digital transposers and the transposers 80 are the tens transposers. This will be understood by an examination of the transposer for slug 2. Taking the contact 85 opposite the numeral 4 multiplying by 2 will give 8, which is the value of the contact 8 at the right-hand side to which the transposing wiring extends. On the other hand, for the tens transposing wiring all 90 amounts of less than 5 extend to the zero contact, since 4 times 2 equals 8, and it is necessary to have at least 5 times 2 before a characteristic one is found in the tens 95 column.

Wiring of multiplying slugs.

The fixed contact plates 75 are wired to the corresponding contacts under the multiplicand keys of the units order. The related and adjacent contact plates 76 are wired to the contacts 30, which are below the multiplicand keys of the tens order. As shown in Fig. 4, there are two groups of 100 multiplying slugs with nine in each group. The upper group of slugs in this figure are wired to the tens, hundreds and thousands sunflowers 48 and 49. The lower slugs, on the other hand, are wired to the units, tens and hundreds sunflowers 46 and 47. Plates 105 77 are wired to the individual contacts of the units sunflower 46. Plates 78, on the other hand, are wired to the individual contacts of the tens segment 47. A similar 110 wiring is likewise provided for the front and back plates on the upper set of multiplying slugs, these extending to the contacts of the hundreds and thousands sunflowers in a similar manner.

115 Referring now to Fig. 4, it will be seen that there are eighteen slugs. (Certain of these have been broken away to show the construction underneath.) The lower group are for convenience designated X and are those slugs which are primarily selected by the units multiplier keys. The upper group, designated Y, are those primarily selected by the tens multiplier keys.

120 The wiring to the contacts cooperating 125 with these slugs will now be described. It 130

will be understood that the bars 73-74 are fixed and that no circuit is established to contacts 75-76 or 77-78 carried by them until a particular slug has been selected and elevated to align the contacts 69-70 and 71-72 therewith. Assume that the multiplication is to be performed of 47 times 86. The multiplication is effected by means of partial products; namely, first by 47 times 6, which is again broken up thus—7 times 6 and 4 times 6. The adding in of these partial products is effected during the first two counter revolutions. This is illustrated diagrammatically in Fig. 18, in which it will be seen that the 2 derived from the digit in the sub-product 42 is added in at the first counter revolution. The 4 derived from the tens column of the product of 6 times 40 is concurrently added in during the first revolution of the counter. During the next revolution of the counter there is added in the 4 in the tens column derived from the 42 product and the 2 in the hundreds column from the 6 times 40 multiplication.

With the above explanation the circuit will now be traced.

The depression of the number 6 multiplier key and the closure of the cam contacts 31-32 at the proper time in the machine cycle establishes a circuit to the number 6 call magnet 38 and selects the number 6 slug of the X group for elevation. This slug is then subsequently elevated and finds that the number 7 contacts 75-76 of the X group are alive, having previously been rendered so by the depression of the units number 7 multiplicand key and the closure of its contacts. A circuit path is then established through the number 7 contacts 75-69, through transposing wire to the number 2 controlling contact 71-77, and thence through a suitable wire to the number 2 controlling contact on the first sector 45 of the units sunflower 46 (see Fig. 15). At the same time, the circuit is established through contacts 76-70, the number 4 controlling contacts 72-78 and thence to the number 4 controlling contact on the second sector of the tens sunflower 47.

Concurrently with the selection of the number 6 slug of the X group, current has flowed across the cross-wire 81, Fig. 17, to the number 6 selecting magnet over the Y group of slugs. This slug, upon being elevated, finds that the number 4 "tens" multiplicand key contact is active and establishes a circuit path as follows: through number 4 contact 75-69, number 4 contact 60 71-77 to the number 4 controlling contact on the first sector on the tens sunflower. Concurrently on the bank contacts opposite the number 4 multiplicand key controlled contact, a circuit path is established thus; 65 from number 4 contact 76-70, number 2 con-

tact 72-78 to the number 2 controlling contact point on the second sector of the thousands sunflower 48. The partial product of 47 times 6 is now completely set up by the activation of the proper contacts on the sunflowers. Thus:

$$\begin{array}{r}
 47 \\
 \times 6 \\
 \hline
 24 \\
 42 \\
 \hline
 78
 \end{array}$$

In the above product it is to be noted that the 4 in the first line is derived from 6 times 4 and not 6 times 7.

The Lake counter is now operated two revolutions, on the first revolution accumulating 42 from the first sectors of the sunflowers. After the counter has made one revolution the usual circuit breaking devices employed in this counter and not herein specifically illustrated break the counter magnet circuits prior to the accumulating operation upon the second revolution. Then on the second revolution the amount 24; i. e., 240, is accumulated from the second sectors of the proper sunflowers. After these two revolutions of the counter have taken place, the slugs are all released and descend to normal position for the next part of the cycle. This releasing of the slugs is effected by the double step cam 43.

It is now desired to add in the other partial product; i. e., 47 times 80. Before this operation can be started the number 6 units setting in the multiplier must be ineffective. Accordingly, towards the end or directly after the second revolution of the counter the cam contacts 31-32 open and shut off the supply of current to the multiplier contacts 30 under the unit keys. Subsequently, the cam contacts 33-34 close and permit the depressed member 8 multiplier key to select the number 8 slugs on both the X and Y groups for subsequent elevation. As before a proper cross-wire 81 (Fig. 17) conducts the current from the Y group to the X group. The slugs are then elevated as before and, upon reaching their upper point, find that the number 7 multiplicand key controlled contact is alive. A circuit path is now established through the number 7 contact, through the number 8, left slug contacts to the number 6 right slug contact and thence to a wire leading to the number 6 contact point upon the third sector of the tens sunflower 47 (Fig. 16). Similarly, the back slug contacts establish a circuit from the 8 multiplicand key contact through the number 5 contact, and thence to the number 5 controlling contact on the fourth sector of the hundreds sunflower 48. This gives a partial product of 7 times 8 or 56.

The above selection of sunflower points was obtained by means of the X group of

slugs, the current flowing through the cross-wire 81^a. Concurrently the Y group had established circuits from the number 4 key contact through the number 2 right-hand contact of the slug to the second controlling contact point of the third sector of the hundreds sunflower 48. The circuit was also established to the number 3 controlling contact point of the fourth sector of the thousands sunflower 49. This completes the setting of the partial products and the counter then makes two more revolutions; namely, the third and fourth. At the third revolution 26 is added in on the hundreds and tens wheels and on the fourth revolution 35 is added in on the thousands and hundreds wheels, thus giving a final product of 4042 set up on the counter.

It will be understood that certain slugs have the wiring of the sub-product contact points extending to a multiplicity of points on the various sunflowers. It will be found, however, that wherever there is a double connection, such double connections are upon successive sectors of the sunflower and the actuation of the counters being only controlled by one sector at a time, this double energization does not lead to any confusion in the result.

The cam contact devices 31—32 and 33—34 need only be provided for the multiplier keys and the multiplicand keys, upon being depressed, are adapted to directly close their circuits to the fixed contact points on the bars 73.

Concurrently with the setting up of the product upon the counter wheels, the product will be set up upon the type wheels 90, Fig. 12. Near the end of the cycle the pin 89', (Fig. 2) strikes the spring retracted lever 92, which is in a suitable manner connected with and serves to operate printing hammer 93. Subsequently, the pin 29 strikes the pivoted member 28 and releases all of the depressed keys. During this part of the cycle the segment 60 is raised and the machine is made ready for another operation.

Multiplying machines are not new, but so far as I am aware, there is no machine in which multiplicand and multiplier figures can be in any way set up and their product obtained by as simple and direct an operation of the machine as has herein been set forth. This result is rendered possible in the machine above described by the employment, as I have now pointed out and by the use of what I have termed multiplying slugs and the use of two sets of keys, one set to render active those contacts which correspond to the digits of the multiplicand, the other to select that or those slugs which correspond to the digits of the multiplier and bring them into operative relation with the active multiplicand contacts. I believe this invention to be broadly new. This being the case the

specific construction of the means which I have shown for carrying out the invention becomes of secondary importance and may be almost indefinitely modified.

What I claim as my invention is:—

1. In a multiplying machine the combination with contacts corresponding to the digits of the multiplicand and means such as a bank of keys for setting up or connecting such contacts with a source of current, of multiplying slugs such as are herein described corresponding to the digits of the multiplier and other means such as a second bank of keys for selecting the slugs and bringing the selected slugs into operative electrical relation to the multiplicand contacts, a counter and means intermediate the slugs and said counter for connecting the active product indicating contacts of the slugs to the appropriate counter mechanisms for registering the numerals corresponding to the active product contacts.

2. In a multiplying machine the combination with contacts corresponding to the digits of the multiplicand and means such as a bank of keys for setting up or connecting the desired contacts with a source of current, of multiplying slugs corresponding to the digits of the multiplier containing two sets of contacts, one adapted to engage the multiplicand contacts the other electrically connected with the contacts of the first set in such order as to indicate the product of the first named contacts and the digit to which the slug corresponds and other means such as a second bank of keys for selecting the slugs and bringing the selected slugs into operative electrical relation to the multiplicand contacts, a counter and means intermediate the slugs and said counter for connecting the active product indicating contacts of the slugs to the appropriate counter mechanisms for registering the numerals corresponding to the active product contacts.

3. In a multiplying machine the combination with contacts corresponding to the digits of the multiplicand and means such as a bank of keys for connecting the desired contacts with a source of current, of other means such as a second bank of keys, multiplying slugs corresponding to the digits of the multiplier and adapted when selected by the keys of the second bank and brought into operative relation to the multiplicand contacts to control the circuits from the active multiplicand contacts to contacts indicating the product of such active contacts and the digit to which the selected slug corresponds, a counter and power operated means for continuing the circuit from the said product indicating contacts to the appropriate counter mechanism for registering the numerals which said contacts represent.

4. In a multiplying machine the combina-

tion of two rows of stationary contacts for the digits of each order of units in the numbers which the machine is adapted to handle as a multiplicand, and nine multiplying slugs for each order of units in the multiplicand, a bank of keys for connecting multiplying contacts to a source of current, another bank of keys for selecting and moving to operative position any desired multiplying slugs, a counter and means intermediate the slugs and said counter for connecting the active product indicating contacts of the slugs to the appropriate counter mechanisms for registering the numerals corresponding to the active product contacts.

5. In a multiplying machine the combination of two rows of stationary contacts for the digits of each order of units in the numbers which the machine is adapted to handle as a multiplicand, two corresponding rows of product contacts and nine multiplying slugs for each order of units in the multiplier with cross connections which, when the slugs are brought to operative position connect the active multiplicand contact with the product contacts which indicate the product of the said active contacts and the digit corresponding to the particular slug selected and brought into operative position, a counter and means intermediate the product contacts and the said counter whereby the active product contacts effect a corresponding registration operation of the counter.

35 6. In a multiplying machine the combination of double rows of stationary contacts for the digits of each order of units in the numbers which the machine is adapted to handle as a multiplicand, nine multiplying slugs for each order of units in the multiplier with cross connections which when the slugs are brought to operative position connect the active multiplicand contacts with product contacts which indicate the product of the active contacts and the digit corresponding to the particular slug selected and brought to operative position, timed circuit controllers which successively select and bring into operation the multiplying slugs for the different order of units and throw them out of operation after their action, and counter timed circuit controllers which cause the active product indicating contacts of the several series of slugs to register the numerals to which they correspond in said counter.

7. In a multiplying machine comprising stationary multiplicand contacts, movable multiplying slugs and such means as keys for connecting the desired multiplicand contacts to a source of current and for selecting the desired multiplying slugs and a counter, the combination of the following instrumentalities adapted for operation as follows: a manually operated driving shaft, means

operative thereby during the first part of its revolution to reset the counter wheels to zero, means operated during the next part of the revolution to move the selected multiplier slugs of the first order of units into operative position, means operated during the next part of the revolution to cause the active contacts of the operative slugs to register the numerals corresponding thereto on the counter, means operated during the next part of the revolution to throw out of action the selected slugs and to bring into action slugs corresponding to the next higher order of units, means for causing the active contacts of such slugs to operate the counter, and means operated during the next part of the revolution to print the total registered by the counter.

8. An electrical multiplying device comprising setting elements for the multiplier and multiplicand, an electrically-controlled counter, and means for controlling counter-controlling circuits conjointly by the multiplier and multiplicand setting elements to thereby control the actuation of said counter to accumulate the product.

9. An electrical multiplying device comprising setting elements for the multiplier and multiplicand, an electrically controlled device upon which the product is set up, and means for conjointly controlling electrical circuits by the multiplier and multiplicand setting devices for controlling the operation of the said device and setting up the product thereon.

10. In a calculating device, an accumulator, means for actuating the same, a plurality of electrical contact elements representing multiplication tables for controlling said operating means, and multiplier and multiplicand keys for controlling the operation of said elements.

11. In a calculating device, product receiving means, electrically controlled means for controlling the actuation of said product receiving means, means comprising multiplying slugs including electric circuits adapted to establish differential circuits in accordance with the selection of circuits leading thereto for controlling the last mentioned means and multiplier and multiplicand setting elements for selecting said slugs for operation and for selecting the electrical circuits leading thereto.

12. In a calculating machine, in combination with means adapted to receive a plurality of successive sub-product items, means comprising keys for setting up multiplier and multiplicand items which form said sub-products, means controlled by certain keys for selectively selecting electrical transposing means for operation, means controlled by other of said keys for selecting circuits for cooperation with said selected transposing means, and controlled by the

conjointly selected circuits and by said transposing means for controlling elements which are adapted to control the entering of the items into sub-product receiving means.

13. In a multiplying machine, an accumulator, electrical actuating means for said accumulator, contact-making means having multiplication table characteristics for controlling said actuating means, and multiplier and multiplicand setting-up means for controlling said contact-making means.

14. In a multiplying machine, an accumulator, electrical actuating means for said accumulator, contact-making means having multiplication table characteristics for controlling said actuating means, means for setting up said contact-making means, and means for timing the operation of said contact-making means.

15. In a multiplying machine, an accumulator, actuating means therefor, a plurality of electric contacts associated with said actuating means for rendering the same operative, means for differentially interconnecting said contacts for determining the effect thereof upon said actuating means, and multiplier and multiplicand setting-up elements for controlling the effectiveness of said interconnecting means.

16. In a multiplying machine, means adapted to receive products, differential actuating means therefor, a plurality of electric contact with provisions for controlling circuits which in turn control said differential devices, means for differentially interconnecting said contacts for determining the effect thereof upon said differential devices, and multiplier and multiplicand setting up elements for controlling the effectiveness of said interconnecting means.

17. In a computing machine adapted for multiplying, comprising in combination, an electrically controlled accumulator, electrically controlled means for setting up items to be added into said accumulator, and timing means for controlling the order in which the several items are so added.

18. In a computing machine, an electrically controlled accumulator, multiplier and multiplicand setting elements, means controlled by said elements for setting up sub-products, and controlled timing means for establishing electrical circuits for successively introducing said sub-products into said accumulator.

19. In a multiplying machine, a plurality of electrical transposing members representing multiplication tables, means for selectively rendering said members operative in accordance with a digit of the multiplier, means representing a digit of the multiplicand adapted to cooperate with said member for producing a product, and means for receiving such product.

20. In a multiplying machine, a plurality of electrical switching members representing multiplication tables, means for selectively rendering said members operative in accordance with a digit of the multiplier, means representing a digit of the multiplicand adapted to cooperate with said member for producing a partial product, and means for accumulating a plurality of said partial products.

21. In a multiplying machine, a plurality of members having electrical circuits therein with multiplication table characteristics, setting means representing one factor of the product and adapted to control the cooperation of other circuit devices with said members, and product representing means controlled in accordance with such cooperation.

22. A multiplying device comprising in combination a set of multiplier keys, a set of multiplicand keys, electrical devices controlled by said keys for forming products, a driving mechanism, a totalizer, and mechanism actuated by the driving mechanism under the control of the electrical devices for entering the products on the totalizer.

23. In a device of the character described, a plurality of rows of multiplier keys, a plurality of rows of multiplicand keys, a plurality of contacts connected to represent multiplications, means jointly controlled by the keys for selecting contacts and closing them to form products in a plurality of decimal orders, a totalizer, and devices controlled by the closed contacts for transmitting to the totalizer the products on the contact devices.

24. In a device of the character described, a plurality of rows of multiplier keys, a plurality of rows of multiplicand keys, a plurality of contacts constructed and connected to represent products, means jointly controlled by the multiplier and multiplicand keys for selecting contacts and closing them to form a plurality of partial products, a totalizer, and means controlled by the aforesaid contacts for successively entering the partial products on the totalizer.

25. In a device of the character described, a plurality of rows of multiplier keys, a plurality of rows of multiplicand keys, a plurality of contacts constructed and connected to represent products comprising a plurality of decimal orders, means jointly controlled by the multiplier and multiplicand keys for selecting contacts and closing them to form products in a plurality of decimal orders, a totalizer comprising an element for each decimal order, and means controlled by the aforesaid contacts for successively actuating the elements of the totalizer in denominational groups.

26. In a device of the character described, a plurality of multiplier keys arranged in denominational groups, a plurality of mul-

- tiplicand keys arranged in denominational groups, a plurality of contacts constructed and connected to represent products comprising a plurality of denominational orders, 5 means jointly controlled by the multiplier and multiplicand keys of corresponding denominational groups for closing said contacts to form products in a plurality of decimal orders, a totalizer comprising an element for 10 each decimal order, and means controlled by the aforesaid contacts for actuating the elements of the totalizer singly or in groups according to the number of decimal orders in the products.
- 15 27. In a device of the character described, a plurality of multiplier keys arranged in denominational groups, a plurality of multiplicand keys arranged in denominational groups, a plurality of contacts constructed 20 and connected to represent products, means controlled jointly by the multiplier and multiplicand keys for closing the contacts to represent a plurality of partial products, a totalizer, a plurality of devices having a uniform movement at each operation, a second 25 set of contacts for each denominational order, and means controlled jointly by said devices and said second set of contacts for entering products on the totalizer.
- 30 28. In a machine of the character described, the combination of a set of multiplier keys arranged in groups corresponding to decimal orders, a set of multiplicand keys arranged in groups corresponding to the grouping of the multiplier keys, a plurality of contacts arranged in decimal groups and connections between contacts and groups of contacts corresponding to various products, 35 a second plurality of sets of contacts grouped to correspond with a plurality of decimal orders and electrical connections between the contacts in said second sets and the product contacts.
- 40 29. In a machine of the character described, the combination of a set of multiplier keys arranged in groups corresponding to decimal orders, a set of multiplicand keys arranged in groups corresponding to the grouping of the multiplier keys, a plurality of contacts arranged in decimal groups and connections between contacts and groups of contacts to represent various products, devices jointly controlled by the multiplier and multiplicand keys to close 45 said contacts to set up thereon a separate product for each decimal order in which keys are operated, and mechanism controlled by the contacts for setting up the numerical values of said products.
- 50 30. In a machine of the class described, the combination of multiplier keys arranged in groups corresponding to decimal orders, a set of multiplicand keys arranged in groups corresponding to the grouping of the multiplier keys, a plurality of contacts arranged in decimal groups and connections between contacts in the same and adjoining groups to represent products, 55 devices jointly controlled by the multiplier and multiplicand keys for selecting and closing contacts to represent a plurality of partial products corresponding to the values of the keys operated and devices controlled by the product contacts for successively transferring said partial products to number set up devices.
- 60 31. In a machine of the character described, the combination of a set of multiplier keys arranged in groups corresponding to decimal orders, a set of multiplicand keys arranged in groups corresponding to the grouping of the multiplier keys, a plurality of contacts arranged in decimal groups and connections between contacts in the same and adjoining groups to represent products, 65 devices jointly controlled by the multiplier and multiplicand keys for selecting and closing contacts to represent a plurality of partial products corresponding to the values of the keys operated and devices controlled by the product contacts for successively transferring said partial products to number set up devices.
- 70 32. In a machine of the character described, the combination of a set of multiplier keys arranged in groups corresponding to decimal orders, a set of multiplicand keys arranged in decimal groups, a plurality of groups of contacts and means for connecting the contacts and groups of contacts to correspond with multiplication tables, devices jointly controlled by the multiplier and multiplicand keys for selecting and closing contacts to represent products of the key values, differential mechanism, and means for operating the differential mechanism under the control of the product contacts.
- 75 33. In a machine of the character described, the combination of a set of multiplier keys arranged in groups corresponding to decimal orders, a set of multiplicand keys arranged in groups corresponding to the grouping of the multiplier keys, a plurality of contacts arranged in decimal groups and connections between contacts in the same and adjoining groups to represent products, 80 devices jointly controlled by the multiplier and multiplicand keys for selecting and closing contacts to represent products of the key values, differential mechanism, and means for operating the differential mechanism under the control of the product contacts.
- 85 34. In a calculating device, product receiving means, electrically controlled means

- for controlling the actuation thereof, said means comprising selectable multiplying slugs having differential circuits therein, means for establishing said circuits in accordance with one factor of the product, means for selecting the slugs for operation in accordance with the other factor of the product, and means including electrical contact devices for successively applying said products to said product receiving means.
35. In a multiplying machine, a set of multiplicand keys, a set of multiplier keys, contacts controlled by the multiplicand keys, a movable element for each multiplier key carrying connections which are arranged according to multiples of the associated multiplier key, a driving mechanism, and means actuated by said mechanism under control of the multiplier keys for actively moving the aforesaid elements to establish multiplying relation with the multiplicand contacts.
36. In a multiplying machine, a set of multiplier keys, a movable element for each multiplier key carrying connections arranged according to multiples of the value of the associated multiplier key, said elements being normally in an ineffective position, means controlled by each multiplier key for moving the associated element to effective position, a set of multiplicand keys, and contacts controlled by the multiplicand keys and rendered effective by the aforesaid movable elements.
37. In a machine of the class described, the combination with a plurality of rows of multiplier keys, of a normally ineffective element for each key constructed to represent the products of the key value multiplied by said value or by the value of any of the other keys in the same row, multiplicand keys, devices controlled jointly by said multiplicand keys and the aforesaid elements to establish connections representing the total of the products of multiplier and multiplicand key values, total indicators, mechanism for actuating said indicators under control of the connections established by the aforesaid devices, and means requiring operation of said mechanism for rendering effective any desired one of the aforesaid elements.
38. In a machine of the class described, the combination with a totalizer, of mechanism for actuating it, a plurality of rows of multiplier keys, an element for each key normally in ineffective position and constructed to represent the products of the key value multiplied by said value or by the value of any other key in the same row, means requiring operation of the actuating mechanism and a multiplier key for moving the element corresponding to the key to effective position, multiplicand keys, means controlled by the aforesaid elements and the multiplicand keys for establishing connections representing the products of the multiplier and multiplier key values, and means whereby said connections control the totalizer actuating mechanism.
39. In a multiplying machine, a multiplier keyboard, a multiplicand keyboard, a plurality of series of contacts, means controlled from the two keyboards for establishing a plurality of partial products in the series of contacts, a set of product indicators, driving devices for the indicators, means actuated by the driving devices for accumulating the aforesaid partial products in a total product on the indicators, and devices for automatically clearing said indicators at the beginning of a multiplying operation of the driving devices.
40. In a multiplying machine, a device upon which the numerical value of a product may be set up, electrical actuating means for said device, contact making means having multiplication table characteristics for controlling said actuating means, and multiplier and multiplicand setting up means for controlling said contact making means.
41. In a calculating device, a device upon which values of a product may be set up, means for actuating the same, a plurality of electrical contact elements representing multiplication tables for controlling said actuating means, and multiplier and multiplicand keys for controlling the operation of said elements.
42. A multiplying device comprising in combination multiplier setting devices, multiplicand setting devices, electrical devices controlled by both of said setting devices for forming products, a driving mechanism, a product receiving device, and mechanism actuated by the driving mechanism under the control of the electrical devices for entering the products into the said receiving device.
- In testimony whereof I hereto affix my signature.

JAMES W. BRYCE.
